UNITED STATES PATENT OFFICE.

GEORGE M. WILLIAMS, OF ELIZABETH, NEW JERSEY.

DESIGN FOR AN EYELET.

46,487.

Specification for Design.

Patented Sept. 29, 1914.

Application filed July 7, 1914. Serial No. 849,601. Term of patent 14 years.

To all whom it may concern:

Be it known that I, GEORGE M. WILLIAMS, a citizen of the United States, residing at Elizabeth, in the county of Union and State of New Jersey, have invented a new, original, and ornamental Design for Eyelets, of which the following is a specification, reference being had to the accompanying drawing, forming part thereof, wherein—

Figure 1 is a plan view of an eyelet show-

ing my new design upon an enlarged scale. Fig. 2 is a cross section through the eyelet taken on the line 2—2 of Fig. 1.

I claim:

The ornamental design for an eyelet, as shown.

GEORGE M. WILLIAMS.
